Inventor:

Dr. H. Humphrey.

UNITED STATES PATENT OFFICE

IRL W. HUMPHREY, OF TERRE HAUTE, INDIANA

AUTOMATIC THERMOSTATIC AUTO FUEL MIXER

Application filed February 12, 1927. Serial No. 167,748.

My invention relates to that class of devices, whereby heated vapor or steam is generated by the heat in the exhaust manifold of an automobile engine and automatically introduced into the manifold and whereby, by means of thermostatic action, the flow of gas into the manifold is decreased as the flow or supply of heated vapor is increased, and vice versa.

10 The objects of my invention are: first, to provide a device whereby water stored in a container, will be heated and vaporized, by heat radiated from the engine of a gas motor, and said vapor or steam will be automatically 15 inducted into the intake of the engine and properly mixed with the gas whereby the engine is driven; second, to provide such a device which will be operated automatically by means of, properly adjusted levers and thermostatic connections; third, to provide such 20 a device, so connected and thermostatically operated and regulated, that when the speed of the engine is increased and incidentally the heat radiated from the engine increased, a 25 greater supply of vapor or steam will be mixed with a proportionately decreased flow of gas and vice versa, when the speed of the engine is decreased the supply of vapor will diminish and the flow of gas will increase; 30 fourth, to provide such a device, whereby much greater mileage will be obtained from a fixed supply of liquid fuel and fifth, to provide such a device, whereby the introduction of vapor or steam properly mixed with the 35 gas will tend to prevent the accumulation of carbon in the engine.

These objects I attain by means of the mechanism illustrated in the accompanying drawings in which:—

40 Figure 1, is an elevation of the device attached to the engine of an automobile, parts of the engine being shown in outline.

Figure 2, is a detail of the thermostatic 45 member.

Similar letters and numerals refer to similar parts throughout the several views.

The letter A indicates a common type of gas engine, of which the letter a indicates the 50 cylinder-case, the letter b the manifold, the

letter c the intake and the letter d the heating-jacket, of the engine.

The numeral 1 indicates a cylindrical container, which is mounted, by means of suitable means of attachment, upon the manifold 55 of the engine and adjacent thereto. The numeral 2 indicates a metal apron attached to and pendant from said cylindrical container, which is curved to fit snugly over the curved side of the manifold of the engine and 60 to extend downwardly and lie flatly against the engine cylinder-case a, to which it is attached by stay-bolts.

A pipe 4 is tapped into the top of the cylindrical container and leads downward to 65 a valve 5, and a pipe 6 extends from said valve 5 to the intake of the manifold, into which it has fluid passage connection.

The valve-stem 7 of the valve 5 extends 70 downwardly and is attached to a forked lever 8, for the purpose hereinafter set forth.

A thermostat comprising a coiled spring 9, the outer end of which is angled and adapted to fit flatly against the apron 2 to which it is attached, a pendant shaft 10, which is attached to the inner end of the coiled spring, and a suitable box-like housing 11, which is mounted upon said apron immediately above the carburetor 12 of the engine. 75

A forked-lever 13, similar in form and 80 length to the forked-lever 8, is attached near the lower end of the shaft 10 and a yoke-like connection-rod 14, is mounted upon the extreme lower end of said shaft 10, and serves to connect said shaft with said upwardly 85 projecting stem 15 of the carburetor valve in such manner that the valve-stem is actuated by the movement of the shaft 10 of the thermostat.

A connecting-rod 16 is pivotally mounted 90 between the forked ends of the levers 8 and 13, and causes them to operate in unison.

When said device is mounted upon and in connection with the engine, the water within the cylindrical container will be heated by 95 the radiation of heat from the engine and vapor developed thereby, will be conducted by suction, to the intake of the manifold of the engine and mixed with the gas fuel supplied through the carburetor of the engine. 100

The heat generated by the operation of the engine is radiated from the cylinder-jacket, and heats the coil-spring of the thermostat thereby causing said spring to expand or contract as the heat is increased or decreased, respectively.

The operation of the thermostat shaft, by expansion or contraction of the coil-spring, opens or closes the valve of the carburetor, thereby regulating the flow of gas into the manifold, in proportion to the speed of the engine and the incidental heating of the cylinder-jacket.

In like-manner the operation of the thermostat shaft, through the connecting-rod 16 and the forked-lever 8, will actuate the valve 5 and increase the flow of vapor into the intake of the engine, when the speed and temperature of the engine are increased, thereby causing a large supply of vapor to mix with a proportionately diminished flow of gas; and when the speed and incidental production of vapor is diminished, the thermostat shaft will open the valve of the carburetor wider and proportionately close the valve 5, thereby automatically injecting a mixture of fuel richer in gas and proportionately leaner in vapor.

The advantages claimed for my device over other similar devices used heretofore for similar purposes, consist in the automatic and proportionate alteration of the mixture of gas and vapor by the mere change in the speed of the engine, in the increased power attained by the vaporized mixture of fuel attained, the decreased carbonization of cylinders and valves attained by the mixture so provided and in the decrease of the gas required to operate the engine.

What I claim as new and desire to secure by Letters Patent, is:—

In an automatic thermostatic auto-fuel mixer, the combination with an internal combustion engine, of a water-container, mounted upon and adapted to be heated by contact with the manifold of said engine, a metal apron attached to and pendent from said water-container and side of the crank-case of the engine, a tube in fluid-passage connection with the top of said water-container, and a cutoff-valve located in said tube, a tube leading from said cutoff-valve to an inlet provided at the base of the intake of the engine, a forked lever fixed upon the projecting end of the valve-stem of said cutoff-valve, a thermostatic member comprising a coil-spring attached to said apron and adapted to expand when heated by radiation from the engine, and a shaft attached at its upper end to the free end of said coil-spring, a forked-lever fixed upon the lower end of said shaft, a connection-rod pivotally connecting the outer ends of said two forked-levers, a fork-like connection mounted upon the extreme lower end of said shaft and in operative connection

with the stem of the needle-valve of the carburetor of the engine, a lever fixed upon said shaft and adapted to operate in unison with the lever attached to the valve-stem of said valve, a connecting-rod extending between said two levers and adapted to operate the said two valves in unison.

IRL W. HUMPHREY.
